UNITED STATES PATENT OFFICE

ISAAC HARTER, OF DONGAN HILLS, NEW YORK, ASSIGNOR TO THE BABCOCK & WILCOX COMPANY, OF BAYONNE, NEW JERSEY, A CORPORATION OF NEW JERSEY

METALLIC BAFFLE

Application filed June 19, 1925. Serial No. 38,199.

My present invention relates to baffles for water tube boilers, and more particularly to baffles which extend parallel to the water tubes, and will be best understood from the following description and the annexed drawings, in which Fig. 1 is a front view, partly broken away, showing a row of water tubes and the filling pieces therebetween constituting a baffle; Fig. 2 is a section along the line 2—2 of Fig. 1; Fig. 3 is a section similar to Fig. 2 showing a modification and Fig. 4 is a somewhat diagrammatic illustration on a small scale showing the disposition of the baffle in relation to a set of tubes of a Stirling boiler.

Like reference characters indicate like parts throughout the drawings.

As is well understood, in certain types of water tube boilers, such, for instance, as Stirling boilers, baffles are arranged parallel to the water tubes to direct the flow of the hot gases. Such baffles are illustrated at 8 and 9 of Fig. 4, the former extending down from the drum 10 along the front of the bank 25 of water tubes, and the latter extending up from the drum 11 along the rear of the bank.

In the baffle of my present invention, I utilize a row of water tubes as part of the baffle and install baffle elements in the space 30 between the tubes, these baffle elements being preferably formed of sheet metal and arranged in position between the tubes with a large surface of the baffle elements contacting with the surfaces of the relatively cool water tubes so that the heat will be carried away 35 from the elements and prevent their destruction.

As best shown in Figs. 1 and 2, a plurality of baffle elements 2 are placed end to end in the spaces between adjacent water tubes 1, to form with the tubes a complete wall or baffle. The baffle elements 2 are shaped, as indicated in section in Fig. 2, so that they have body portions provided with flanges 3 along each 40 edge thereof, these flanges being curved, as indicated at 4, on a radius of curvature which is the same as the radius of curvature of the outside of the water tubes 1 between which they are to be placed. The element 2 may be 45 inserted between the tubes by forcing the same

in, whereupon one or both of the flanges 3 will spring sufficiently to permit the elements 2 to be inserted.

In the modification shown in Fig. 3, the baffle elements 5 have flanges 6 formed on their edges similar to the flanges 3 of the element 2, but instead of having these flanged extending on opposite sides of the baffle element, these flanges 6 extend on the same side of the element 5 and are curved, as indicated at 7, to conform to the outer surface or curvature of the tubes 1 between which they are to be installed. These baffle elements can likewise be inserted by pressure, whereupon the flanges 6 will spring sufficiently to 55 permit the same to be inserted.

It will thus be seen that the baffle elements 2 or 5, together with a row of tubes 1, constitute a baffle wall of the proper dimensions, and the curved surfaces of the flanges of the 60 elements 2 or 5 coming into close contact with the outside of the water tubes 1 over a considerable area to provide a very effective means for transferring the heat from the elements 2 or 5 to the tubes 1. It will be seen 65 that each flange of an element contacts with 70 and bears against a tube on a surface extending on both sides of the center line of the row of tubes in which the elements are disposed. Each element may be considered as formed 75 of these two flanges, connected by a body extending between the flanges, and this body 80 may take any desired form, two forms being exemplified in Figs. 2 and 3, respectively.

By my invention a cheap and effective 85 baffle may be formed which can be readily maintained in place. It will also be noted that by reason of the tight fit between the water tubes and baffle elements, these elements will remain in position to form a baffle, as at 90 8, which does not have to be supported from below.

I claim:

1. A baffle element for water tube boilers comprising a metal plate having a flange at 95 each of its opposite edges, said flanges being curved transversely to fit the opposing walls of the adjacent water tubes, the body of said baffle element being wider than the distance between the tubes.

2. A baffle element for water tube boilers comprising a metal member having a flange at each of its side edges curved to fit the water tubes, said flanges extending at an acute angle to the main body portion of said baffle element. 70
3. A baffle for a water tube boiler comprising a row of water tubes spaced apart and sheet metal elements in the spaces between the tubes, each of said elements having a main body portion wider than the distance between tubes and curved flange portions along opposite edges of said main body portion, said curved flanges fitting snugly against said water tubes. 75
4. A baffle for a water tube boiler comprising a row of water tubes spaced apart and metal elements in the spaces between the tubes, each of said elements having a main body portion and curved flange portions along opposite edges of said main body portion, said curved flanges being disposed at an acute angle to said main body portion and fitting snugly against said water tubes. 80
5. A baffle for a water tube boiler, comprising a row of water tubes spaced apart, and metal elements in the spaces between the tubes, each of said elements having a main body portion and curved flange portions along opposite edges of said main body portion, said curved flanges being disposed at an acute angle to said main body portion and resiliently pressing against said water tubes. 85
6. In combination, a plurality of tubes disposed in a row and yieldable metallic baffle elements disposed between the tubes in the row, each element comprising a body having curved flanges integral therewith, and each flange contacting with the adjacent face of adjoining tubes and extending on both sides of the center line of said row of tubes. 90
7. In combination, a plurality of tubes disposed in a row and yieldable metallic baffle elements disposed between the tubes in the row, each element comprising curved flanges, each flange contacting with the tubes adjacent thereto and extending on both sides of the center line of said row of tubes, and a body connecting said flanges and integral therewith. 95
8. In combination, a plurality of tubes disposed in a row and baffle elements disposed between the tubes in the row, each element comprising a body portion, and yieldable means integral with said body portion resiliently holding said element in position independently of other elements. 100
9. In combination, a plurality of tubes disposed in a row and baffle elements disposed between the tubes in the row, each element comprising a body portion, and yieldable means integral with said body portion resiliently holding said element in position independently of other elements by contacting with adjoining tubes. 105
10. In combination, a plurality of tubes disposed in a row and baffle elements disposed between the tubes in the row, each element comprising a body portion, and yieldable means disposed between said body portion and adjoining tubes and resiliently holding said element in position independently of other elements. 110
11. In combination, a plurality of tubes disposed in a row, and a resilient baffle element disposed between adjacent tubes and contacting therewith, the resilience of said element forming means to hold it in position between the tubes. 115
